MORRIS SCHOENFELD, OF RORSCHACH, SWITZERLAND.

CORD-LAYING DEVICE FOR EMBROIDERY MACHINES.

1,248,556.

Specification of Letters Patent.

Patented Dec. 4, 1917.

Application filed March 16, 1916. Serial No. 84,613.

To all whom it may concern:

Be it known that I, MORRIS SCHOENFELD, a citizen of the United States, and resident of Rorschach, Switzerland, have invented a new and useful Cord-Laying Device for Embroidery-Machines, of which the following is a full, clear, and exact specification.

The cord-laying-in devices most in use are those wherein a bundle of cords is tensioned from one end of the embroidery machine to the other. For the laying-in operation, a cord is taken from the bundle and engaged into a special holder in order that the said cord can be brought near to the fabric and within the reach of the needles for fastening it into the embroidery. The workman who on one end of the machine engages the cord into said holder, has to draw the cord out of the bundle, to carry it over the whole length of the machine and to fasten it at the other side of the same; in this way, the cord is brought into its position ready for operation. The modern embroidery machines are in the most cases constructed only for two embroidery rows and comprise only a few middle frame uprights, so that in thus following the cord for the lower embroidery row the workman is not seriously hindered thereby. For the drawing-in of a cord for the upper embroidery row, there is no hindrance at all. This may be the reason why in practice the said operation has hitherto not been considered as troublesome, although the successive drawing-in of the cords in reality gives rise to certain inconveniences.

The conditions are, however, different in the recent great and long embroidery machines with a relatively great number of middle frame uprights. Here, the attendant who besides has a great deal to do has not sufficient time for correctly drawing in the cords if he will not temporarily stop the machine. The same troubles arise in embroidery machines wherein the needle supports are not fixed to longitudinal beams, but to frame uprights arranged from distance to distance, in which case the workman, in drawing-in the cords, has to take over or around the said uprights.

The object of the present invention is to facilitate the drawing-in of the cords in embroidery machines. According to the invention, the cord laying-in device comprises in combination with cord supplying bobbins removable holders near the ends of the machine, provided with a row of openings for

the introduction of one cord in each opening and so arranged as to hold the cords parallel to each other orderly arranged and to allow drawing-in of all the cords at a time 60 from one end of the machine to the other for their easy transferring into operative position.

Preferably, the holders are interchangeably mounted on frame parts so as to be 65 capable of being transferred from one end of the machine to the other and vice-versa.

For the drawing-in of the cords, it is advantageous to arrange at the side of the cord furnishing bobbins a guide having a row of 70 openings for the parallel drawing-in of the cords, said guide being fixed and preferably provided with a clamping member for fastening all the cords in the openings of said guide. 75

The holders are each provided with a clamping member for clamping-in the cords drawn into their openings.

While the holders are preferably constituted by rakes having their teeth directed 80 upward for receiving between them the cords, the aforesaid guide consists preferably of a bar with a row of holes for the drawing-in of the cords so as to prevent them from being lifted out of said holes. 85

The drawings represent an embodiment of the subject of the invention. Figure 1 is a diagrammatic longitudinal view of an embroidery machine having five rows of needles; Fig. 2 is a vertical transverse section through said machine on a larger scale; Fig. 3 shows a plan view of one group of cords; Fig. 4 shows by a side elevation one of the cord holders; Fig. 5 shows by a side elevation the guide with clamping member 90 95 and Fig. 6 represents two special, but well known working tools.

The uprights *a* of the machine frame carry the needle bars *c* by means of the brackets *b*. Near the ends of the machine are arranged 100 two vertical control rods *d*, *e* which can be moved through the medium of a jacquard- or hand-controlled rod *f* and levers *g*, *g*¹ interconnected by a link rod *i* and joined by links *h* to the respective control rods *d*, *e*. The 105 rods *d*, *e* carry arms *l*, *m*, respectively. On these arms are mounted the holders *o* for holding in parallel tensioned condition the different cord groups corresponding to the embroidery rows. Among said holders, that 110 on the right hand placed near the end of the machine where cord furnishing bobbins *s*

are arranged, serves at the same time for the drawing-in of the corresponding cord group inasmuch as the cords thereof furnished by the respective bobbins and passing through a 5 guide p fixed on the arms m are fixed in said right-hand holder and drawn through its medium over the whole length of the machine from the right-hand end to the left-hand end of the same, so that this drawing-in of the cords is simultaneously and orderly produced at a time for all cords of the same group. Each of the holders o , see Fig. 4, consists of a rake o^1 having its teeth directed upward for receiving between them the respective cords, and of a fulcrumed clamping cover o^2 which can be lowered over said rake o^1 and in the lowered position clamps in all the cords lying in the openings between the rake-teeth. The cord guide p , which is arranged on the cord furnishing side of the machine, consists of two parallel pierced plates p^1 , see Fig. 5, and an interposed, tightly guided pierced slide p^2 which, after drawing-in the cords through the holes of 15 the plates p^1 , is so displaced relatively to the plates p^1 as to clamp in or secure the cords in the drawing-in holes. The arms l, m carry besides each a well known cord-laying-in finger q (Fig. 6) for receiving that cord of 20 the group which is to be transferred into operative position, and a well known cutter r (Fig. 6) which is designed to cut off the embroidered-in cord. As soon as a cord of each 25 group is put into the fingers q on both ends 30 of the machine, it is in position ready for the laying-in operation of the cord. The transferring of the cord into the position for its laying-in or stitching to the embroidery fabric is obtained by lowering the rods d, e 35 through the medium of the lever system f, g, g^1 . After the laying-in of the forward 40 cords of the different groups into the embroidery work, the said rods are again raised by means of the lever system f, g, g^1 and in 45 this operation the cutter r cuts off the cords held in place by the embroidery work and in contact with the inner sharp edge of the operative hook of the cutter, as it is well known in this kind of machines. The cord ends are 50 then still held fast in the holders o . The holders o are removably mounted on brackets o^3 which are adjustably fixed on the arms l, m , so that they can easily and rapidly be removed therefrom. This detachable 55 connection of the holders o with their brackets o^3 is obtained, as represented in Fig. 3, by the arrangement wherein in each holder a weak curved leaf spring o^4 presses against one edge of the base plate of the rake o^1 and 60 pushes the same with its other edge into a re-curved part o^5 of the bracket o^3 . If it is desired to remove the holder, a pressure is exerted upon it in the direction toward the spring o^4 , which is then compressed or flattened, so that the base edge of the rake o^1

which is on the opposite side to the spring, can be withdrawn from the recurved part o^5 of the bracket; the connection is thus broken and the holder ready for being taken away.

The mode of use of the described device is 70 for example the following:

The cords are unwound from the bobbins s , drawn successively, but in the desired order through the holes of the guide p , the slide p^2 of which is in inoperative position, and 75 then laid on the right hand side of the machine parallel side by side between the teeth of the respective holder o , wherein they are then clamped fast, whereupon the said holder is removed from its bracket and utilized for drawing in all the cords at a time over the whole length of the machine from 80 one end to the other. After this drawing-in the said holder is fixed to the left-hand bracket o^3 , while on the right-hand side of 85 the machine there is mounted another similar holder o with the teeth of its rake entering from below between the cords of the drawn-in row, whereupon the clamping cover o^2 of the second holder is put down to 90 clamp fast the cord in the holder. This second holder gives the advantage that the cords coming from the supply bobbins, after consumption of the length of cord in operative position, are ready and in proper order 95 for their further drawing-on through the machine, inasmuch as for this further supplying operation the said holder may serve as drawing-in tool. After the slide p^2 of the 100 guide p has been displaced to clamp fast the cords in the same, the cords of the group are fixed in tensioned condition and in an orderly arranged row and they can then successively be brought into their operative 105 position.

What I claim is:

1. A cord laying-in device for embroidery machines, comprising the combination of movable supporting members near the ends of the machine, removable holders thereon provided with a row of openings, each opening designed to receive one cord from cord supplying bobbins at one end of the machine, and with means to hold fast the cords therein parallel to each other, said holders being arranged to allow drawing-in of all the cords at a time orderly arranged side by side from one end of the machine to the other for their easy and proper drawing-in and tensioning, and controlling means for 110 actuating said supporting members to transfer the cords into their operative position.

2. A cord laying-in device for embroidery machines, comprising the combination of movable supporting members near the ends of the machine, removable holders thereon provided with a row of openings, each opening designed to receive one cord from cord supplying bobbins at one end of the machine, and with clamping means to clamp 115

fast the cords therein parallel to each other, said holders being arranged to allow drawing-in of all the cords at a time orderly arranged side by side from one end of the machine to the other for their easy and proper drawing-in and tensioning, and controlling means for actuating said supporting members to transfer the cords into their operative position.

10 3. A cord laying-in device for embroidery machines, comprising the combination of movable supporting members near the ends of the machine, interchangeable holders thereon provided with a row of openings, each opening designed to receive one cord from cord supplying bobbins at one end of the machine, and with means to hold fast the cords therein parallel to each other, said holders being arranged to allow drawing-in of all the cords at a time orderly arranged side by side from one end of the machine to the other for their easy and proper drawing-in and tensioning, and controlling means for actuating said supporting members to transfer the cords into their operative position.

4. A cord laying-in device for embroidery machines, comprising the combination of movable supporting members near the ends of the machine, removable holders thereon provided with a row of openings, each opening designed to receive one cord from cord supplying bobbins at one end of the machine, and with means to hold fast the cords therein parallel to each other, said holders being arranged to allow drawing-in of all the cords at a time orderly arranged side by side from one end of the machine to the other for their easy and proper drawing-in and tensioning, and controlling means for actuating said supporting members to transfer the cords into their operative position.

45 5. A cord laying-in device for embroidery machines, comprising the combination of movable supporting members near the ends of the machines, removable holders thereon provided with a row of openings, each opening designed to receive one cord from cord supplying bobbins at one end of the machine, and with means to hold fast the cords

therein parallel to each other, said holders being arranged to allow drawing-in of all the cords at a time orderly arranged side 55 by side from one end of the machine to the other for their easy and proper drawing-in and tensioning, a guide interposed between the cord supplying bobbins and the adjacent cord holder and provided with clamp- 60 ing means to clamp fast the cords, and controlling means for actuating said supporting members to transfer the cords into their operative position.

6. A cord laying-in device for embroidery 65 machines, comprising cord fastening holders arranged so as to be capable of being displaced along the machine for drawing-in the cords from cord supplying bobbins orderly arranged side by side from one end of the machine to the other, said holders consisting each of a rake with upright directed teeth and a clamping fastener to clamp in the cords between said rake teeth.

7. A cord laying-in device for embroidery 75 machines, comprising the combination of movable supporting members near the ends of the machine, removable holders thereon provided with a row of openings, each opening designed to receive one cord from cord 80 supplying bobbins at one end of the machine, and with means to hold fast the cords therein parallel to each other, said holders being arranged to allow drawing-in of all the cords at a time orderly arranged side by 85 90 95

the other for their easy and proper drawing-in and tensioning, a guide interposed between the cord supplying bobbins and the adjacent cord holder and consisting of a plate with holes for the passage of the cords through the same and a clamping slide with similar holes for the cords, allowing to clamp fast the same, and controlling means for actuating said supporting members to transfer the cords into their operative position.

In witness whereof I have hereunto signed my name this 14th day of February, 1916, in the presence of two subscribing witnesses.
